US00D559545S

(12) **United States Design Patent** (10) Patent No.: **US D559,545 S**
Allen (45) Date of Patent: **** Jan. 15, 2008**

(54) **CONTAINER**(75) Inventor: **Richard E. Allen**, Colleyville, TX (US)(73) Assignee: **Boyt Harness Company, L.L.C.**, Osceola, IA (US)(**) Term: **14 Years**(21) Appl. No.: **29/248,082**(22) Filed: **Jul. 27, 2006**(51) LOC (8) Cl. .... **03-01**(52) U.S. Cl. .... **D3/254; D3/262; D3/289**(58) Field of Classification Search **D3/254, D3/262, 276, 289, 292, 294, 904, 905; 206/3, 206/314, 315.1, 315.11, 316.1, 317, 523; 190/900; 224/910-913, 931**

Gun Guard—Double Rifle Case at CTI Warehouse Network. Downloaded May 18, 2007 at <http://www.bow-gun-hunting-sports.com/dyn.htm>.*Primary Examiner—Gary D. Watson*Assistant Examiner*—RoseLynne (Ulm) Cody(74) *Attorney, Agent, or Firm*—Bell, Boyd & Lloyd LLP(57) **CLAIM**

The ornamental design for a container, as shown and described.

DESCRIPTION

FIG. 1 is a front, top perspective view of the container.

FIG. 2 is a rear, bottom perspective view of the container of FIG. 1.

FIG. 3 is a front elevation view of the container of FIG. 1.

FIG. 4 is a top view of the container of FIG. 1; and,

FIG. 5 is a left side elevation view of the container of FIG. 1, the right side being a mirror image thereof.

The portions of the container shown in phantom are not part of the design sought to be patented and are provided for environmental purposes only.
